UNITED STATES PATENT OFFICE.

JAMES F. MAYS, OF BIRMINGHAM, ALABAMA, ASSIGNOR TO MAYS ACCOUNTING MACHINE COMPANY, OF LEXINGTON, NORTH CAROLINA, A CORPORATION OF NORTH CAROLINA.

CALCULATING-MACHINE.

1,301,073.

Specification of Letters Patent. Patented Apr. 15, 1919.

Application filed August 7, 1917. Serial No. 184,921.

To all whom it may concern:

Be it known that I, JAMES F. MAYS, a citizen of the United States, residing at Birmingham, in the county of Jefferson and 5 State of Alabama, have invented certain new and useful Improvements in Calculating-Machines, of which the following is a specification.

The primary object of this invention is 10 the provision of a key-actuated calculating machine of means for obtaining a uniform depth of key stroke for the several keys in a column.

In the specific form of my invention here 15 illustrated, I accomplish this by causing the keys of lower denomination—"1" to "6", for example—to act upon the dial actuator indirectly, while the keys of higher denomination—"7" to "9", for example—operate 20 upon said actuator through a series of compensating levers arranged to give the required differential movement to the actuator.

Another object of my present invention is to provide an improved form of locking 25 mechanism for limiting the rebound of the key actuator.

Other objects will more fully appear from the following description.

The mechanism comprising my present 30 invention is disclosed in my copending application, Serial No. 148,559, filed February 14, 1917.

In order to more fully describe my invention, reference will be had to the accompanying drawings, wherein:—

Figure 1 represents in vertical central section, partly in elevation, a calculating machine embodying my invention;

Fig. 2 is a fragmentary top plan view 40 thereof;

Fig. 3 is a section on the line 3^x—3^x of Fig. 1;

Fig. 4 is a section on the line 4^x—4^x of Fig. 1; and

Fig. 5 is a fragmentary rear elevation of 45 the rebound preventing mechanism.

Similar reference numerals refer to similar parts throughout the several views of the drawings.

The machine illustrated in the accompanying drawings comprises, among other parts, a machine casing having a top 1, a back plate 2, an intermediate transverse vertical plate or partition 3 interposed between 50 the banks of keys 4 on one side and the oper-

ating mechanism for the dials 5 on the other side, which dials are mounted upon shafts 6 journaled at their inner ends on a bearing bar 7 attached to the partition 3, and at their outer ends in a cross bar 8 made fast 60 to the front end of the machine (not shown). Below the banks of keys is arranged a bottom guide plate 9 made fast to the plates 2 and 3 and provided with holes to receive and form a bottom guide for the lower ends of 65 the key stems which at the end of their down stroke engage the base plate 10 of the machine.

These key stems are made of flattened metal strips having their lower portions 70 within the casing twisted at right angles and provided with rack teeth 11, as seen in Figs. 4 and 5. These teeth 11 on each key are adapted to mesh with the teeth 12 of its respective toothed sector 13, one of which is made fast on each rocker shaft 14 opposite the "7", "8" and "9" keys of each column. The keys of lower denomination than "7" in each column carry a lateral pin 15 which projects into an elongated slot 16 at the 80 outer end of a lever 17, 17^a, 17^b, 17^c, 17^d or 17^e, as the case may be, each of these levers projecting at their rear ends through suitable slots in the back plate 2 and having a pivotal bearing on pins 18 in a back bracket 85 19 formed by pairs of angle plates which have lugs out-turned and made fast by screws 20 to the back plate.

The several keys from "1" to "6", inclusive, in each column, are severally connected 90 to a corresponding lever 17, 17^a, etc., and these several levers for each column of keys are arranged in two banks of three each, one bank being arranged to pass on one side of the column of keys and of a common rack 95 key 21 and the other bank on the opposite side thereof. This rack key 21 carries a stepped cross bar 22 with offset shoulders of graduated height disposed to be engaged respectively by the levers 17, etc., and to be moved downwardly thereby for the predetermined distance, depending on the denomination of the key depressed. The several levers have a variable stroke due to varying lengths and being pivoted at different distances from the common rack key 21, and this will bring the lower edges of the levers at different heights where they pass over the bar 22 for which reason it is desirable to shape the bar so that it will engage each 110

lever. The operating connection thus provided between the key 21 and the levers can be made in other ways, but that shown is ample to illustrate my purposes.

5 It is intended that each key 4 shall have exactly the same length of down stroke, but it will be obvious that the angular movement of its respective lever, 17, 17^a, etc., will depend upon the length of the lever and the 10 distance of its pivot from the common rack key. In this manner I obtain very simply and effectively the differential dial driving movement from a uniform key movement. I prefer to interpose the levers, as the operating 15 connection between the first six keys of lower denomination in each column, as it would be difficult to work out a plan for the uniform key stroke with a direct connection without interposition of some equivalent means, and I consider this form shown the simplest for my purposes. Each common rack key 21 carries teeth 11 which mesh with teeth 12 on its respective sector 13 on shaft 14 and serve to rotate the latter in the 20 same manner as the teeth 11 on the key stems for the "7", "8" and "9" keys.

As illustrated in Fig. 1, I employ coil springs 23 which are fastened to the top plate 1 and one of which is connected to each key stem to effect its return after being depressed. For the sake of clearness, in Fig. 1 I have omitted all but one such springs. The lower end of either rack bar 21 carries a spring seat 24 which bears 30 against a coil spring 25 surrounding its stem and interposed between the seat 24 and the bottom 9, thus providing for the return of the common rack keys. The upper end of these rack keys are received in angled guide 35 plates 26 which are secured to the top plate 1 and extend down into position to engage the upper end of each rack bar so as to guide it in all of its operating positions. Each of the key stems is provided with a supplemental set of teeth 27 below and spaced from the teeth 11, and these teeth on each key are adapted to mesh with teeth 28 on a respective sector 29 made fast on a bottom rocker shaft 30 journaled in the plates 2 and 3.

40 As a means for bringing the sectors 13 and 29 into toothed engagement with their respective key stems, I provide pins 31 and 32 on each key stem, and I provide each sector with an arm 33, it being noted in Fig. 5 that 45 the arm 33 of sector 29 stands in engagement with the pin 32, whereas the arm of the sector 13 is in the path of, but is spaced substantially from its respective pin 31. The object of this is to cause each key stem 50 as depressed to engage and impart a rocking movement to its respective lower rocker shaft 30 in advance of engaging and rocking its respective rocker shaft 14 through which it drives its respective dial. In other 55 words, I provide what may be termed a lost-

motion driving connection between the key stems and the dial operating rocker shafts 14 with a positive driving connection to the lower or supplemental rocker shafts 30. The purpose of this will be understood by 70 reference to Fig. 3, where it is seen that each corresponding pair of rocker shafts 14 and 30 carry fast thereon coating lock pins 34 and 35 which are so disposed relatively that, when a pair of shafts 14 and 30 are in initial position, the lock pin 35 will engage under and set at right angles to the lock pin 34 (see the pins on the left hand shafts, Fig. 3). This position of the lock pins positively locks the dial operating shafts 14 against 80 movement and the preliminary movement imparted by pin 32, arm 33 and sector 29 to the rocker shaft 30, will rock the pin 35 to its upper dotted position, clearing the pin 34 in advance of the engagement of the 85 key with the sector 13. After the pins are thus unlocked, both shafts are free to take the full movement imparted to them by the key depressed and on the return the pins will automatically resume their locked position, thus holding the dial operating shafts 14 locked at all times except after the keys have been substantially depressed and prevent a rebound of the drive mechanism which imparts motion from the shafts 14 to 95 the dials.

90 The dial driving mechanism comprises a toothed sector 36 made fast on the forward end of each shaft 14 beyond the plate 3 and meshing with a pinion 37 which turns freely 100 on shaft 6, and through a ratchet drive imparts a counterclockwise movement, as viewed from the front, to the ratchet wheel 38 fast on the shaft 6. The pinion 37 is returned to initial position with the sector 36 105 responsive to the action of a coil spring 39 on the shaft 14 and it is to prevent a rebound from this return movement that the lock pins are provided. The counterclockwise movement imparted to the shaft 6 will 110 advance the dial 5 proportionately with the value of the key depressed.

115 It will be understood, of course, that suitable mechanism may be provided for carrying from a dial of lower to higher denomination. Such mechanism, however, constitutes no part of my present invention.

Without limiting myself to the specific mechanism herein shown, what I claim is:—

1. A calculating machine comprising a 120 column of keys, a dial, key actuated dial operating mechanism comprising an actuator directly driven by keys of higher denomination in said column, and differential leverage means forming a driving connection between said actuator and other keys of lower denomination in said column.

125 2. A calculating machine comprising a column of keys, a dial, key actuated dial operating mechanism comprising an actuator, 130

- a direct operating connection between said actuator and the keys of higher denomination in said column, differential leverage means directly actuated by the keys of lower 5 denomination in said column, and a common transmission element driven by said differential leverage means and adapted to impart motion to its actuator.
3. In a calculating machine, a column of 10 keys, a dial, a dial operating rock shaft actuated directly by the keys of higher denomination in said column, levers operated by the keys of lower denomination in said column, an actuator common to the keys of 15 lower denomination and driven by the levers operated by said keys and disposed to receive motion from each lever proportionate to the value of the key controlling it, and means to drive said rock shaft by said actuator.
4. A calculating machine comprising a column of keys, a dial operating rock shaft actuated directly by the keys in said column of a denomination of seven and upward, 20 levers operated by the keys of lower denomination than seven in said column, a common actuator for the keys from one to six, inclusive, and driven by said levers and disposed to receive a motion from each lever proportionate to the value of the key controlling it, and means to drive said rock shaft by said actuator.
5. In a calculating machine, a column of keys, a number dial, a mechanism common 35 to all of the keys of said column to rotate said dial, means directly driven by the keys of higher denomination to operate said mechanism, and means driven indirectly by keys of lower denomination to operate said 40 mechanism, each indirect driving means comprising pivoted levers each connected at its free end to a key, and an actuator common to all of said levers and adapted to engage the same at varying distances from their respective fulcrums and to transmit 45 differential motion therefrom to the dial actuating mechanism.
6. In a calculating machine, a plurality of 50 keys, a dial, dial actuating mechanism comprising a movable member common to said keys, a stop carried by said member, a supplementary movable member common to said keys, a stop carried by said second member and adapted to coöperate with said first-mentioned stop to lock the first-mentioned 55 member against rotation, means operable by the downward movement of a key to rotate said second member to unlock said first member, means operable by the same key to subsequently operate said first-mentioned member, springs for returning said members to normal, the stop on the supplementary member acting to limit the rebound of the first-mentioned member.
7. In a calculating machine, a plurality of 60 keys, a dial, dial actuating mechanism comprising a rocker shaft common to said keys, a stop carried by said shaft, a supplementary shaft, a stop carried thereby and adapted to coöperate with said first-mentioned stop to lock said first-mentioned 65 shaft against rotation, means operable by the downward movement of a key to rotate said second shaft to unlock the first shaft, means operable by the same key to subsequently operate the first-mentioned shaft, 70 springs for returning said shafts to normal, the stop on the supplementary shaft acting to limit the rebound of the first-mentioned shaft.
- In testimony whereof I affix my signature. 75
JAMES F. MAYS.
